3 Claims. (Cl. 131—121)

ABSTRACT OF THE DISCLOSURE

A method modifying tobacco to produce less irritants when burned comprising exposing it to at least one megarad of gamma radiation.

Our invention relates to a method of treating tobacco to reduce the amount of irritants formed when it is burned.

Fresh tobacco smoke contains substances which are irritating and harmful to body tissue. Attempts to remove these substances based on a step of filtering the smoke have had varying degrees of success. Filters which are highly efficient in removing tars make undesirable changes in the taste of the smoke, and yet do not remove some irritants.

It has been discovered that fresh smoke from burned tobacco contains a significant number of free radicals. As is well-known, free radicals are highly reactive, and, consequently, their presence in tobacco smoke is undesirable since they may combine with other particles in the smoke to form harmful substances, or they may react directly with body tissue. It is desirable to reduce the number of free radicals in fresh tobacco smoke.

It is one object of our invention to provide a method of treating tobacco to reduce the amount of irritants formed when the tobacco is burned.

It is another object to provide a method of treating tobacco to change the substances produced during burning without making undesirable changes in the taste of the smoke.

It is another object to provide a method of reducing the number of free radicals in fresh tobacco smoke.

Other objects of our invention will be apparent from the following detailed description and the appended claims.

In accordance with our invention we have provided a method of treating tobacco comprising exposing said tobacco to at least one megarad of gamma radiation.

Tobacco treated in accordance with our invention burns to produce smoke containing 25–30 percent less tar, about 50 percent less toluene, and about 50 percent fewer free radicals than smoke from untreated tobacco.

The figure is an infrared analysis of the fraction of smoke condensate distilling above 150° C. from non-irradiated and irradiated cigarettes. As can be seen by comparing the curve for the smoke from the irradiated cigarette with the curve for the smoke from the non-irradiated cigarette, irradiation has decreased significantly the amount of tar produced upon burning tobacco.

While the mechanism by which irradiation of tobacco reduces the quantity of tars, toluene, and free radicals produced upon subsequent burning is not known, and we do not therefore wish to be bound by any theory, it is believed that gamma radiation breaks some of the complex molecules into fragments which either remain in that form or combine with other molecules or fragments. The result in either case is that the product contains different particles than did the untreated tobacco. These new particles, being different, upon burning produce reaction products which differ from those produced by

2

burning non-irradiated tobacco. Unexpectedly, the products formed from irradiated tobacco are less irritating to body tissue than are the products formed from non-irradiated tobacco.

In carrying out our process the tobacco may be irradiated at any time in its processing from harvesting until after packaging for sale to the consumer.

The quantity of radiation absorbed must exceed one megarad. A rad is a measure of the energy absorbed per unit weight and is equal to 100 ergs per gram. A megarad is equal to 10^6 rads.

While the irradiation may be carried out to over 100 megarads, at this level the taste of the smoke produced on burning is adversely affected, and the dosage should be kept below 100 megarads, preferably from 5 to 75 megarads. The optimum dose is from 10 to 25 megarads.

The rate of irradiation is not critical and may be carried out from rates of less than 0.1 to greater than 10 megarads per hour. The limitations of the radiation facility employed will normally fix the irradiation rate.

Having thus described our invention, the following examples are offered to illustrate it in more detail.

Example I

25 Cigarettes irradiated to a level of 10 megarads by irradiating for 10 hours at a rate of 1 megarad per hour and non-irradiated control cigarettes were placed in a smoking machine designed to smoke 15 cigarettes simultaneously. Each cigarette was smoked in turn, once each 30 minute. A puff consisted of a 35-milliliter intake of air over a 2-second period. The smoke was collected in a cold trap cooled with Dry Ice and propylene glycol. The collected smoke was washed from the trap twice with trichlorotrifluoroethane and three times with methylene 35 chloride. The collected solutions were vacuum-distilled and the following fractions were collected:

Fraction	Vacuum	Temperature
1	33 mm. Hg.	Room temperature to 50° C.
2	1 mm. Hg.	50° C. to 150° C.
3	Remaining residue.	

45 Infrared analyses performed on these fractions showed that (1) in fraction 1 there were several compounds present in the smoke from non-irradiated tobacco which were absent in smoke from irradiated tobacco; (2) there was little difference between the samples in the second fraction; and (3) the smoke from irradiated tobacco 50 showed a substantially smaller amount of all components in the third fraction, i.e., the "tars," compared to the smoke of non-irradiated tobacco. The infrared analysis of the third fraction is given in the figure. As can be seen 55 from this figure the amount of tar in the smoke from the irradiated tobacco is from 15% to 25% less than the amount in the smoke from the non-irradiated tobacco.

Example II

60 Cigarettes irradiated to a level of 10 megarads and non-irradiated control cigarettes were smoked in the smoking machine of Example I. Each cigarette was smoked at a rate of four puffs per minute and 100 milliliters of air was taken per puff. The smoke was trapped as in Example I, the condensate was dissolved in benzene and examined 65 in an electron spin resonance spectrometer within 15 minutes of collection. The relative signal intensities per milligram of condensate were 2.24 for the irradiated tobacco and 5.10 for the non-irradiated tobacco. This shows that the smoke from irradiated tobacco contained 70 less than 50 percent as many free radicals as the smoke from non-irradiated tobacco.

3
The above examples are offered to illustrate and not to limit our invention. Modifications such as changes in irradiation time and dose may be made without departing from our invention.

Having thus described our invention, we claim:

1. A process of treating harvested tobacco for the purpose of reducing tars and free radicals comprising exposing it to at least one megarad of gamma radiation.

2. The process of claim 1 wherein the tobacco is irradiated to a level of 5 to 75 megarads.

3. The process of claim 1 wherein the tobacco is irradiated to a level of 10 to 25 megarads.
